UNITED STATES PATENT OFFICE

RALPH A. DUFF, OF NEBRASKA CITY, NEBRASKA

ATTACHMENT FOR INTERNAL COMBUSTION ENGINES

Application filed July 20, 1929. Serial No. 379,801.

This invention is an attachment for internal combustion engines, and is adapted to admit water vapor to the charge passing into the manifold of the engine.

5 The objects of the invention are, first, to provide means for atomizing or spraying water into the intake; second, to provide means for controlling the intake of air by which the water is atomized; third, to provide means for controlling the supply of water; fourth, to provide means for operating the air controlling means in predetermined time relation to the throttle valve; fifth, to provide means for operating the 10 water controlling valve in predetermined relation to the air controlling valve; and sixth, to generally improve the construction and enhance the utility of attachments of this character.

20 With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

25 A practical structure for carrying out the invention is illustrated in the accompanying drawings, wherein:

Figure 1 is a fragmentary view in elevation of an intake manifold with an attachment constructed in accordance with the invention in place thereon;

Figure 1a is a fragmentary view in elevation of a portion of the control, broken away from Figure 1;

30 Figure 2 is a sectional view taken on the line 2-2, of Figure 1;

Figure 3 is a fragmentary plan view, part in section on the line 3-3, of Figure 1;

Figure 4 is a cross section through the 35 valves at the slot 22.

The device comprises a water reservoir, which is in communication with an air intake pipe. A valve, operating in proper timed relation to the throttle valve, is provided for controlling the intake of air, and a

water controlling valve is operated by, and in proper relation to the air control valve. There is also provided adjustable means connected to the throttle control for operating the valves.

Referring to the drawings by characters of reference, 1 designates the usual intake manifold, and a fragment of an intake pipe 2 is shown attached thereto. In this pipe 2 is the usual butterfly throttle valve 3, to the projecting end of the stem of which is rigidly attached a crank 4. The usual operating rod 5 has pivotal connection at one end to the crank 4, so that the throttle may be actuated through the manipulation of the rod.

55 The intake manifold 1 is provided with an inlet aperture 6, as seen in Figure 2, adapted to align with the longitudinal bore of the leg 7 of a T. The longitudinal bore of the leg 7 of the T extends into a projection or nipple 7' formed on and preferably integral with the head of the T and opens to the atmosphere at the end of the nipple. The leg 7 of the T is formed with the usual connecting flange 8, apertured to receive the machine screws, or other connecting elements 9, by which the device is connected to the intake.

60 The cross arm of the T is vertically disposed, and is formed with a longitudinal bore which communicates with the longitudinal bore of the leg 7. From the lower end of the cross arm of the T a pipe 10 extends laterally, and establishes communication between the bore of the cross arm of the T and a water reservoir 11. The reservoir 11 may be provided with a laterally extending filling chamber 12, the inlet opening of which is normally closed by the screw plug 13. This chamber may be screened from the main chamber of the reservoir 11 to insure clear 65 water entering the main chamber.

70 The lower end of the cross arm of the T is interiorly threaded to receive a spray nozzle 14, the upper end of which extends into the longitudinal bore of the leg 7 of the T, 75 and defines with the countersunk portion of the bore of the cross arm of the T, an annular groove 14', the purpose of which will soon be described. After the nozzle 14 has been 80 threaded into place, the lower end of the 85

cross arm of the T is closed by a screw plug 15 or the like.

A cylindrical valve 16 normally closes the longitudinal bore of the leg 7 to prevent intake of air therethrough, and this valve is longitudinally bored or cored for a portion of its length, and the tubular end of the valve seats in the annular groove 14'. The stem of the valve 16 extends, with a close sliding fit, through the apertured packing nut 17, and the extending end thereof is formed with spaced annular flanges 18 between which the prongs 19 of the bifurcated end of one arm of a bell crank lever engage. The bell crank lever is pivotally supported on a bracket 20, which is clamped in place on the upper end of the cross arm of the T by the before-mentioned packing nut 17.

Mounted within the bore of the valve 16, and slideable longitudinally thereof, is a needle valve 21 having a short longitudinally disposed slot 22 formed therein, through which slot passes a pin 23, disposed diametrically of the stem of the valve 16 and having a free sliding fit in the slot 22. A compression spring 24 is located in the bore of the valve 16, and is confined between the upper end of the needle valve 21 and the upper end of the bore, and serves to retain the needle valve in its lower or seated position, even after the valve 16 has started to open, and until the pin 23 engages the upper end of the slot 22 and causes the needle valve to travel with the valve 16. As will be understood, the slot 22 may be made of a length to give the best results, the length depending on the size and character of engine on which the attachment is to be used.

The other arm 25 of the bell crank lever 40 through which the valve 16 is operated, is provided with a series of apertures a, b, c, d, and e, spaced longitudinally thereof and adapted to selectively receive the angled end of a connecting rod 26, the other end of which rod has pivotal connection with an apertured ear 27, extending radially from a sleeve 28 which encircles and is slideable longitudinally of the operating rod 5. A stop collar 29 is slideable on the rod 5 and may be 50 clamped in selected positions thereon by means of a set screw 30 or the like. The position of this stop collar is changed to accommodate the collar to the position of the sleeve when the end of the connecting rod 26 is 55 changed to another hole in arm 25.

With the device as herein shown, the connecting rod is connected in hole a when a one and three fourths inch throttle is used; and, when a ninety degree throttle with a one 60 and one half inch radius is used, connection to hole b causes the valve 16 to move in unison with the throttle; connection at aperture c causes the valve to begin to move when the throttle has opened to fifteen degrees; connection at hole d causes the valve 16 to begin

to move when the throttle has been opened thirty degrees and connection at aperture e causes the valve to begin to open forty-five degrees behind the throttle.

The operation is as follows:

The device is connected, as shown, between the inlet valves of the engine cylinders and the throttle valve, and the tank is filled with water or other desired liquid. The connecting rod 26 is adjusted to permit entrance of water with a greater or less throttle opening, as desired, and the device is ready for operation.

When the engine is running with the throttle closed, that is, idling, no water is admitted to mix with the charge, and admission of air through the nipple 7' and leg 7 is prevented by the valve 16, which is seated. This will prevent disturbing the partial vacuum formed in the intake manifold by the suction of the engine, and will insure proper suction to deliver the charge to the engine.

When the throttle is opened the valve 16 will begin to open and, when sufficiently unseated, will permit air to be drawn through the nipple 7' and leg 7 to the manifold 1. As the throttle is opened further the pin 23 will come into contact with the end of the slot 22 and the needle valve 21 will travel in unison with the valve 16 and permit water to be sprayed from the end of the nozzle 14, under the action of the inrushing air.

What is claimed is:

1. A device for attachment to the intake manifold of an internal combustion engine, including a member having an air inlet passage adapted to discharge into the manifold, a nozzle opening into the passage, a water reservoir in communication with the nozzle, a tubular valve controlling the flow of air through the passage, a spring pressed valve in the tubular valve normally engaging the nozzle to shut off the supply of water from the nozzle to the air passage; means for shifting the tubular valve longitudinally to control the flow of air through the passage, and means actuated by the tubular valve when moved past a predetermined point for opening the nozzle controlling valve therein.

2. A device for attachment to the intake manifold of an internal combustion engine including a member having an air passage therethrough adapted to open into the manifold, a nozzle in said member adapted to open into the passage, a liquid reservoir communicating with the nozzle, a tubular valve slidably mounted in said member and normally extending around the end of the nozzle and across the air passage to cut off the supply of air through the passage, a spring-pressed valve seated within and slideable longitudinally of the tubular valve, for normally engaging and closing the nozzle, means for operating the throttle valve of the engine, and an adjustable connection between said

means and the tubular valve for shifting said valve longitudinally independently of the spring-pressed valve, means on the two valves cooperating to unseat the spring-pressed 5 valve during the approach of the tubular valve to its full open position, said valves operating in predetermined relation to the throttle valve of the engine to admit air only when the throttle valve is partly open and 10 thereafter to admit a mixture of air and water when the throttle valve is in full open position.

3. The combination with the manifold of an internal combustion engine having a throttle valve and a rod for actuating the valve, 15 of a member having an air passage therethrough opening into the intake manifold, a nozzle opening into said passage, a water reservoir in communication with the nozzle, a 20 tubular valve normally surrounding the nozzle and closing the air passage, a spring-pressed valve within the tubular valve normally closing the nozzle, an adjustable connection between the rod and tubular valve for 25 opening said valve during the opening of the throttle valve, and cooperating means on the tubular and spring-pressed valves for opening the spring-pressed valve during the continued opening of the tubular and throttle 30 valve, thereby to admit water to the opened air passage.

In testimony that I claim the foregoing as my own, I have hereto affixed my signature.

RALPH A. DUFF.
